DESIGN FOR A TOY CIRCUS FAIR

Joshua L. Cowen, New York, N. Y., assignor to
The Lionel Corporation, New York, N. Y., a
corporation of New York

Application August 17, 1935, Serial No. 58,171

Term of patent 3½ years

To all whom it may concern:

Be it known that I, Joshua L. Cowen, a citizen of the United States of America and a resident of New York, in the county of New York and State of New York, have invented a new, original, and ornamental Design for a Toy Circus Fair, of which the following is a specification, reference being had to the accompanying drawing, forming a part hereof.

The single figure in the drawing is a perspec-

tive view of the toy circus fair showing my new design, the tent and track being permanently secured to the base or support; a portion of the drawing being broken away for convenience in illustration.

I claim:

The ornamental design for a toy circus fair as shown and described.

JOSHUA L. COWEN.
